CLAIM

The ornamental design for a hip pack, substantially as shown and described.

DESCRIPTION

FIG. 1 is a front perspective view of a hip pack, showing our design.

FIG. 2 is a front view of the hip pack of FIG. 1.

FIG. 3 is a back view of the hip pack of FIG. 1.

FIG. 4 is a right side view of the hip pack of FIG. 1.

FIG. 5 is a left side view of the hip pack of FIG. 1.

FIG. 6 is a top view of the hip pack of FIG. 1.

FIG. 7 is a bottom view of the hip pack of FIG. 1; and, FIG. 8 is a front perspective view of the hip pack, with the top opened.

The broken lines illustrate features and surfaces that form no part of the claimed design.

1 Claim, 7 Drawing Sheets
